PICKING MECHANISM FOR LOOMS

William A. Blanchard, Millbury, Mass., assignor
to Crompton & Knowles Loom Works, Worcester, Mass., a corporation of Massachusetts

Application August 26, 1949, Serial No. 112,492

18 Claims. (Cl. 139—147)

1

This invention relates to improvements in picking mechanisms for looms and it is the general object of the invention to provide such a mechanism including resilient members such as springs which are stressed at the beginning of the picking operation and serve not only to keep the picking cam against its actuator but also return the energy stored in them to the picker stick near the end of the picking operation.

In a form of picking mechanism which has gone into use in a well-known type of loom a solid picking shoe or cam is fastened tightly to the picking shaft of the loom. The cam is engaged by a rotating picking ball or roll, and during the picking operation all parts of the picking shoe and shaft act as a rigid unit. As a result of this construction the cam is likely to rebound from the roll with resultant unevenness of operation on successive picking operations, and the cam is prevented from imparting to the shuttle the kind of motion for which it is designed. Furthermore, repeated rebounding is likely to cause breakage of the picking cam or shoe.

It is an important object of the present invention to mount the picking shoe movably on the picking shaft and operatively connect the shoe and shaft by springs so located as to be compressed when the picking roll engages the cam to have stored in them energy which is available for eliminating or reducing the amount of rebound of the cam.

As the picking operation nears completion the springs will be under compression, and it is a further object of the invention to deliver the energy stored in the springs to the shuttle near the end of the picking stroke. This delivery of stored energy is found to improve the flight of the shuttle and in actual experience has the effect of causing the picker to follow the shuttle for a greater length of travel than is the case when the picking shoe is fixed tightly on the picking shaft.

In the usual picking mechanism the wood picker stick is bent during the picking operation and straightens near the end of the picking stroke to give added acceleration to the shuttle. It is a further object of the invention to employ an energy storing means in the train of picking mechanism operative to deliver its stored energy to the picker stick as the latter straightens, thereby imparting an additional motion to the stick simultaneous with its straightening to increase the acceleration of the shuttle.

It is another object of the invention to provide the picking shaft with a key and mount rotatably on the shaft a cam member having a shoulder

2

or surface held against one side of the key by compression springs which exert their forces on the opposite side of the key and are mounted on the cam member. When the cam member is moved by the picking roll the springs are compressed, permitting the shoulder to move away from the key, and at or near the end of the picking stroke the springs return the key into engagement with the shoulder to give added angular motion to the shaft.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a front elevation of one end of a loom having the improved mechanism applied thereto,
20 Fig. 2 is a side elevation looking in the direction of arrow 2, Fig. 1.

Fig. 3 is an enlarged transverse vertical section on line 3—3, Fig. 2, showing the picking shoe parts in normal position,
25 Fig. 4 is a side elevation looking in the direction of arrow 4, Fig. 3.

Fig. 5 is a vertical longitudinal section on line 5—5, Fig. 3,
30 Fig. 6 is a diagrammatic view similar to Fig. 3 showing the position which the parts assume during a picking operation, and

Fig. 7 is a diagram showing the sequence of operations of the parts of the invention.

Referring particularly to Fig. 1, the loom frame 35 supports top and bottom shafts 11 and 12 the latter of which is provided with a picking arm 13 carrying a picking roll or ball 14. The bottom shaft rotates every other pick of the loom so that the roll 14 is in the low part of its travel on alternate picks of the loom. Another roll not shown herein is located at the opposite end of the loom and is displaced 180° from the roll shown in Fig. 1. The lay 15 is provided with shuttle box 16 containing a shuttle S which is propelled by a picker 17 operatively related to the upper end of a picker stick 18. The latter is preferably though not necessarily made of wood and is pivoted as at 19 to a rocker foot 20. A lug strap 21 extends around the picker stick and is connected to a sweep stick 22 the left end of which as shown in Fig. 1 is connected to a sweep or power arm 23. The shuttle box may be provided with a usual form of binder 24 which checks the shuttle as the latter enters the shuttle box and also offers

some resistance to motion of the shuttle out of the box at the time of picking.

The matter thus far described is of common construction and operates in the usual manner. The sweep arm 23 is given a motion to the left on alternate picks of the loom when the lay is moved rearwardly and has reached approximately its top center position. At this time the picker stick 18 moves to the left to move the shuttle 8 out of the box 16 and start it on its flight to a similar shuttle box at the opposite end of the loom.

The sweep arm 23 is secured to a picking shaft 30 rockably mounted in front and back bearings 31 and 32 mounted on the loom frame. This shaft extends under the bottom shaft 12 and is ordinarily at right angles to it. The arm 23 may be held in adjusted position along shaft 30 by set screw 33.

The rear part of the picking shaft has front and back screw threads 35 and 36 cut thereon receiving positioning nuts 37 and 38, respectively, held in adjusted position by lock nuts 39. The part 40 of the shaft having the screw threads cut thereon may be of somewhat larger diameter than the front and back ends of the shaft, as suggested in Fig. 5, and has cut therein a key slot 41 which may extend radially from the axis of shaft 30. A key 42 is fitted in the slot 41 and extends a substantial distance above the top of the shaft 30, as shown in Fig. 3.

The picking shoe, designated generally at 44, comprises a cam member 45 having a bore 46 which fits the enlarged part 40 of shaft 30 between positioning nuts 37 and 38. Member 45 has a hub or body portion 47 from one side of which extends the picking cam 48 for cooperation with the picking roll 14. Cam 48 has a working incline 49 having low and high parts 50 and 51, respectively, and is preferably formed with a dwell 52 extending beyond the high part. This dwell is preferably concentric with shaft 12 when the roll 14 is on the high part 51 of cam 48.

The cam member 45 has an elongated shoulder 55 and is provided with a longitudinal pocket 56 which receives the upper part of the key 42, and communicated with three bores 57, 58 and 59 in shoulder 55. Located in each bore is a plunger head 60 normally in engagement with the key 42. Each plunger head 60 may have a lug 61 fitting into the adjacent coil of a relatively strong compression spring 62 located in the associated bore. There will be a spring 62 for each of the bores 57-59, and each spring will have that end thereof opposite the corresponding plunger head 60 engaged with an adjusting screw 66 screw threaded into the shoulder 55 and having a centering lug 67 for its spring. Each screw 66 has a lock nut 68 by means of which the adjusted setting of the screw may be held. The pocket 56, as shown in Fig. 3, extends transversely of shaft 30 a short distance to the right of key 42, and the plunger heads 60 are mounted for slight longitudinal motion in bores 57-59.

Under normal conditions the picking shaft, key, picking member 45, and the springs 62 will be as shown in Fig. 3, the springs being expanded and acting to hold a wall 71 on cam member 45 at the left of pocket 56, Fig. 3, against the left part of the key 42. In Fig. 7 the entire time of the picking operation is indicated at *a*, starting at the left and ending at the right. At the beginning of a picking operation the picking roll 14 will engage the low part 50 of cam 48 and rock the cam member 45 in a counter-clockwise direc-

tion as viewed in Fig. 3. The shuttle, being at rest relative to the lay and being held by the shuttle binder, offers resistance to movement of the picker stick 18, and as a result the shaft 30 tends to remain at rest during the first part of the rocking of the shoe 45 for a time corresponding to *e* in Fig. 7 with resultant compression of the springs 62 and storing of energy in them. During this operation the parts will assume the position shown in Fig. 6 with wall 71 moved to the left of the key 42, and with the springs either entirely, or almost entirely, closed by compression. This relative angular motion of member 45 with respect to the shaft 30 is made possible by the fact that the pocket 50 is somewhat wider than the key 42.

As picking ball 14 continues to roll along cam incline 48 shaft 30 will start to turn and the picker stick will be bent or bowed slightly toward sweep arm 23 for a time corresponding to *f*, Fig. 7. Eventually, enough force will be exerted by the upper end of the stick to cause the shuttle to start moving to the left in shuttle box 16, Fig. 1. For the remainder of the engagement of roll 14 with incline 48 the shuttle will be driven positively by the cam for the time indicated by *d*, Fig. 7. During this part of the picking operation the stick will be bowed and the springs 62 will remain under compression. Thereafter, as the picking ball reaches the end of incline 48 the picker stick will straighten during part at least of the time indicated at *g*, Fig. 7, its upper end moving in the direction of travel of the shuttle to increase the acceleration of the latter. The springs 62 thereupon expand while roll 14 is in engagement with dwell 52 of the cam to give the shaft 30 a slight additional turning motion relative to the picking member 45 to produce an extra acceleration on the part of the picker 17. This extra acceleration derived from expansion of the springs will generally occur during straightening of the stick, and during the last part of the picking operation the shuttle derives acceleration from the fact that the stick is recovering its normal shape and also from the fact that the picker stick is being moved bodily by the springs.

In Fig. 7, *b* represents the time of travel of picker 17, and *c* represents the time roll 14 is moving along the incline 48 of cam 48. When roll 14 leaves dwell 52 the springs will be expanded and key 42 will be against wall 71.

If it should be desired to adjust the degree of compressibility of the springs all of the adjusting screws may be either tightened or slackened, as desired, or if the degree of adjustment is to be very slight then only one of the adjusting screws 66 will be turned. In this way a very small change can be induced in the total force exerted by the three springs.

As already mentioned, there is likely to be some rebound of the cam 48 from the actuator roll 14 during the picking operation. With the springs under compression from near the start of the picking operation, however, if there should be a tendency to rebound the springs will expand sufficiently to hold the cam against roll 14, and in doing so will enable the cam to give to the picker stick the character of motion for which the cam is designed. As the roll 14 approaches the high part 51 of the cam the springs will be under compression, and for this reason the shuttle will be given additional acceleration, as already described.

From the foregoing it will be seen that the invention sets forth a train of force transmitting

mechanism between the picking roll 14 and the shuttle including springs in which energy is stored and then returned near the end of a picking stroke to give increased acceleration to the shuttle. This train also includes the bendable picker stick which recovers its normal form as the springs expand. While the compression of the springs has been set forth hereinbefore as occurring at the beginning of the picking stroke it will be sufficient if the stored energy is accumulated at some point during the picking stroke before the latter is completed. The springs also serve to reduce or prevent rebounding of cam 46 away from roll 14 and thus hold the cam against the roll throughout the travel of the roll along incline 49.

The pocket 56 is slightly wider than the key 42 to permit the relative motion of the member 45 with respect to the shaft 30, as indicated in Fig. 6. Only one of the three adjusting screws need be varied if a slight change only is desired in the total compressibility of all the springs.

This application is a continuation in part of patent application Serial No. 74,059, now abandoned, filed by applicant February 2, 1947.

Having thus described the invention it will be seen that changes and modifications of the foregoing specific disclosure may be made without departing from the spirit and scope of the invention.

What is claimed as new is:

1. In shuttle picking mechanism for a loom having a picking actuator, a picker stick for picking the shuttle, a picking shaft operatively connected to the picker stick, an energy storing means on the shaft including a picking shoe for engagement with the actuator, and compression springs, said energy storing means having energy stored therein by the actuator during the first part of the picking operation and returning said energy for application to the picking stick during the latter part of the picking operation.

2. In picking mechanism for a loom having a shuttle to be picked and a picking actuator, a train of mechanism intermediate the shuttle and actuator including a resilient picker stick which is deformed during the picking operation, a picking shaft operatively connected to the picker stick, a picking shoe mounted on the shaft for angular movement relatively thereto by said actuator, and compression spring means operatively interposed between the shaft and shoe, the relative resistance of the stick and spring means to deformation being such that the actuator when engaging the shoe first compresses the spring means and then bends the picker stick, the picker stick straightening during the latter part of the picking operation and the spring means expanding to cause the shaft to impart motion to the stick simultaneous with the straightening thereof.

3. In shuttle picking mechanism for a loom having a revolving picking roll, a picking shaft rockably mounted in the loom, a picker stick operatively connected to the picking shaft, a picking shoe mounted on the shaft for angular movement relatively thereto by said roll, a key on said shaft within said picking shoe, a plurality of compression springs operatively interposed between the picking shoe and the key, said roll upon engagement of said shoe causing compression of said springs and then rocking of said picking shaft to give the picking stick a picking stroke, said springs expanding near the end of the picking stroke to cause motion of the picking stick

additional to the motion of the stick caused by the roll and shoe.

4. In picking mechanism for a loom having a shuttle to be picked and a picking actuator, a picker stick to pick the shuttle, a picking shaft rockably mounted in the loom, a key on said shaft, a picking shoe rockably mounted on the shaft and having a pocket to receive said key and having a plurality of bores communicating with the pocket and extending transversely of the shaft, a compression spring in each bore operatively related at one end thereof to the key and operatively related to the picking shoe at the other end thereof, said actuator when engaging the shoe compressing said springs to store energy therein prior to the rocking of the picking shaft and thereafter effecting a rocking of the picking shaft to cause movement of the picker stick and the shuttle, said springs expanding near the end of the picking stroke to give back the energy stored in them for the purpose of giving additional motion to the picker stick.

5. In picking mechanism for a loom having a shuttle to be picked and a picking actuator, a picker stick to pick the shuttle, a picking shaft rockably mounted in the loom, a key on said shaft, a picking shoe rockably mounted on the shaft and having a pocket to receive said key and having a plurality of bores communicating with the pocket and extending transversely of the shaft, a compression spring in each bore, a plunger head slidable in each bore intermediate the key and one end of the associated spring, the other end of the spring being operatively related to the picking shoe, said actuator when engaging the shoe member compressing said springs to store energy therein prior to the rocking of the picking shaft and thereafter effecting rocking of the picking shaft to cause movement of the picker stick and the shuttle, said springs expanding near the end of the picking stroke to give back the energy stored in them for the purpose of giving additional motion to the picker stick.

6. In picking mechanism for a loom having a shuttle to be picked and a picking actuator, a picker stick to pick the shuttle, a picking shaft rockably mounted in the loom, a key on said shaft, a picking shoe rockably mounted on the shaft and having a pocket to receive said key and having a plurality of bores communicating with the pocket and extending transversely of the shaft, a compression spring in each bore operatively related at one end thereof to the key and operatively related to the picking shoe at the other end thereof and said actuator when engaging the shoe member compressing said springs to store energy therein prior to the rocking of the picking shaft and thereafter effecting rocking of the picking shaft to cause movement of the picker stick and the shuttle, said springs expanding near the end of the picking stroke to give back the energy stored in them for the purpose of giving additional motion to the picker stick, and an adjusting screw in each bore to vary the normal compression of the associated spring.

7. In picking mechanism for a loom having a shuttle to be picked and a picking actuator, a picking stick for the shuttle, a rockably mounted picking shaft relatively connected to the picking stick, a picking shoe movable angularly on the shaft and positioned for engagement with the actuator, and coil spring means operatively interposed between the shoe and the shaft having the coils thereof normally open, said actuator upon engagement of the picking shoe causing

compression of said spring means and moving the coils thereof into closed order and thereafter causing rocking of the shaft to effect motion of the picking stick and shuttle, said spring means expanding near the end of a picking stroke to exert force on the picking stick tending to move the same in the direction of travel of the shuttle.

8. In picking mechanism for a loom having a shuttle to be picked held frictionally against motion by a shuttle binder, the loom having a picking actuator, a picker stick for the shuttle, a rockably mounted picking shaft operatively connected with the picker stick, a picking shoe mounted on the shaft for angular movement relative thereto and positioned for engagement by the actuator, and compression spring means operatively interposed between the shoe and the shaft, the actuator when engaging the shoe causing compression of the spring means to store energy therein and thereafter causing rocking of the picking shaft to effect movement of the picker stick and cause motion of the shuttle against the action of said shuttle binder, the shuttle during the picking stroke thereof moving away from the binder, said spring means thereupon expanding to exert the energy stored therein against the picker stick to move the latter in the direction of travel of the shuttle to increase acceleration of the latter.

9. In a picking mechanism for a loom having a shuttle to be picked and a picking actuator, a picking stick for the shuttle capable of deformation during the picking stroke but tending to return to the normal form thereof, mechanism operatively interposed between said actuator and picking stick including compression spring means deformable during the picking operation but tending to return to the normal form thereof, said actuator at the start of a picking stroke deforming said spring means first and thereafter effecting deformation of the picker stick, the latter near the end of a picking stroke recovering the normal form and said springs recovering the normal form during recovery of the picker stick of the normal form thereof, whereby the shuttle near the end of the picking stroke has energy imparted thereto by the simultaneous recovery of both the picker stick and the spring means of the normal forms thereof.

10. In a picking mechanism for a loom having a shuttle to be picked by a picker stick, a regularly moving actuator, a picking cam operated by the actuator, operative connections between the cam and the picker stick including resilient means, the actuator upon the engagement of the cam at the start of the picking operation storing energy in the resilient means, and a dwell on the cam engaged by the actuator during the latter part of the picking operation cooperating with the actuator to enable said resilient means to return the energy stored therein to the picker stick to increase acceleration of the shuttle.

11. In a picking mechanism for a loom having a shuttle to be picked by a picker stick, a picking actuator revolving about an axis, a picking cam positioned for operation by the actuator having low and high points, a dwell on the cam extending from the high point thereof concentric with said axis when said actuator is engaging the dwell, and operative connections between the cam and the picker stick including resilient means in which energy is stored by the actuator during the first part of the picking operation, said resilient means returning the energy stored therein while the actuator is in engagement with said dwell to in-

crease the acceleration of the picker stick and shuttle.

12. In a picking mechanism for a loom having a shuttle to be picked by a picker stick, a picking actuator comprising a roll revolving about a fixed axis, a picker shaft rockably mounted on the loom, a picking cam mounted on the shaft for angular movement relatively thereto and in position for operation by said roll, operative connections between the picker shaft and the picker stick, compression springs operatively interposed between the picker shaft and said cam, said roll when engaging the cam at the beginning of a picking operation compressing said springs to store energy therein and thereafter as the picking operation continues effecting angular motion of the picking shaft, picker stick and shuttle, and a dwell on said picker cam engaging said roll during the latter part of the picking operation and effective to hold said cam temporarily in fixed position to enable said springs when expanding to return the energy stored therein to effect rocking of the picking shaft to accelerate the picker stick.

13. In a picker shaft and picking cam assembly for a loom having a picking roll revolving about a fixed axis, a picker shaft constructed to be rockably mounted in the loom, a picking cam having low and high points mounted on the picker shaft for angular movement relative thereto, compression spring means operatively interposed between the cam and the picker shaft, and a dwell on the cam extending from the high point thereof constructed to be concentric to said axis when said roll is in engagement with said high point of the cam.

14. In a picking shoe for a loom picking shaft having a cylindrical bearing part and a key projecting beyond said bearing part, the shoe comprising a cam carrying hub having a bore to fit and move angularly on said bearing part of the shaft, the hub having a pocket therein communicating with the bore to receive the key at one side thereof, and resilient means in the pocket engaging the hub at the other side of the pocket and effective when the hub is fitted to said bearing part to engage the key and hold the latter yieldingly against the hub at said one side of the pocket.

15. In a picking shoe for a loom picking shaft having a cylindrical bearing part and a key projecting beyond said bearing part, a picking cam carrying hub having a bore to fit and move angularly on said bearing part of the shaft, the hub having a pocket therein communicating with the bore and extending lengthwise of the latter to receive said key at one side thereof, and a metallic spring for engagement with the key located in said pocket at the other side of said pocket and effective when the hub is fitted to said bearing part to hold the key against the hub at said one side of the pocket, but yieldable to permit angular movement of the hub on said bearing part.

16. In picking mechanism for a loom, a picking shaft having a cylindrical bearing part, a key on the shaft projecting beyond said bearing part, a picking shoe formed with a cam carrying hub having a bore fitting and movable angularly on said bearing part of the shaft, the hub having a pocket therein communicating with the bore and extending lengthwise of the latter and receiving said key at one side thereof, and resilient means in said pocket at the other side thereof engaging the key and normally holding the key against the hub at said one side of the pocket but yield-

able to enable the hub to turn angularly on said bearing part.

17. In picking mechanism for a loom, a picking shaft having a cylindrical bearing part, a key on the shaft projecting beyond said bearing part, a picking shoe provided with a cam carrying hub having a bore fitting and movable angularly on said bearing part of the shaft, the hub having a pocket therein communicating with the bore and extending lengthwise of the latter and receiving said key at one side thereof, and a metallic spring in the pocket at the other side thereof engaging the hub and key and normally under a given stress to hold that part of the hub at said one side of the pocket against said key, said spring capable of yielding under increased stress to enable the hub to turn on said bearing part and move said part of the hub away from the key.

18. In picking mechanism for a loom, a picking shaft having a key slot and key therein, an adjusting nut on the shaft at each end of the slot movable along the shaft when turned thereon, a picking shoe provided with a cam carrying

hub movable angularly and longitudinally of the shaft, and resilient means in the shoe operatively interposed between the hub and the key normally holding a part of the hub against the key but yielding to permit relative angular movement of the hub with respect to the shaft and movement of said part of the hub away from said key, said resilient means being movable with the hub when the latter is moved lengthwise of the shaft incident to adjustment of said nuts and remaining operatively interposed between the hub and the key for all adjusted positions of the hub along the shaft.
